UNITED STATES PATENT OFFICE.

HENRY S. NODDINGS, OF SPRINGFIELD, MASSACHUSETTS.

SAFETY-RAZOR-BLADE HOLDER.

Application filed November 5, 1924, Serial No. 747,886. Renewed October 12, 1926.

My invention relates to improvements in devices for holding safety-razor blades while being sharpened or honed, and consists essentially of a pair of jaws held together in normally closed position by means of a rod and spring of certain peculiar shape or formation, one of said jaws being provided with short studs or posts arranged to fit into holes in openings in a blade, together with such other parts and members as may be necessary or desirable in order to render the holder complete and serviceable in every respect, all as hereinafter set forth.

The jaws of this device have parts which grip the blade, and each of which forms an angle of approximately ten degrees, as will presently more clearly appear. And said jaws are so constructed exteriorly that, when either jaw and the exposed cutting edge of a blade, which is in place in the holder, are supported on a given plane, there is a clearance between such plane and the portions of the jaw and blade that are between the bearing parts, and it is with this plane that the associated gripping part forms an approximately ten-degree angle, and said plane forms with a plane similarly applied to the other jaw and the other side of said cutting edge an included angle of approximately twenty degrees, which is the included angle of said cutting edge. In other words, the included angle of each cutting edge of the blade is twenty degrees, and the jaws are so constructed that either can be supported on a stone or hone, when a blade is in place in the holder, in such a manner as to leave the aforesaid clearance, and, at the same time, insure the sharpening of the blade at the proper angle.

The primary object of my invention is to produce a holder, of the character described above, with which a safety-razor blade held therein can be accurately sharpened or honed, such holder being comparatively simple and inexpensive in construction. A blade in this holder is so held and can be so guided that the exposed edge of said blade is applied to the stone or hone at exactly the proper angle, and without liability to rock or roll, which makes it possible for an inexperienced person to sharpen the blade without injuring the same.

Another object is to provide a blade holder in which the blade can be easily and quickly placed in position, and from which it can be as easily and quickly removed.

The holder consists of few parts, among which is a spring that serves the purpose, not only of normally retaining the jaws in closed position, but of assisting in holding the members together and retaining them in proper relative positions at all times.

Other objects and advantages will appear in the course of the following description.

I attain the objects and secure the advantages of my invention by the means illustrated in the accompanying drawings, in which—

Figure 1 is a side elevation, on an enlarged scale, of a safety-razor-blade holder which embodies a practical form of my invention, the blade being shown in position ready to be sharpened; Fig. 2, a longitudinal section through said holder and blade, taken on lines 2—2, looking in the direction of the associated arrow, in Fig. 1, and, Fig. 3, a rear end elevation of the holder.

Similar reference characters designate similar parts throughout the several views.

The holder comprises two generally similar jaws 1, a hinge or pivot rod 3, a spring 4, and two short posts or studs 5. A safety-razor blade is represented at 6. Blades of this character are made with holes therein, as is well understood, and the studs 5, which are set in one of the jaws at a short distance back from the front edge thereof, are so spaced apart and of such a size as to be received and fit snugly within the aforesaid holes. In Fig. 2, the stud 5 therein appearing is shown in one of the holes in the blade 6. The studs 5 are set back the proper distance from the front edge of the jaw 1, in which they are located, to leave a sufficient portion of the blade 6 engaged thereby to project beyond said edge and enable the exposed cutting edge of said blade to be sharpened. The heads of the studs 5 are inclined to correspond with the inclination of the jaw 1 which closes over the same.

The blade 6 has two oppositely-disposed cutting edges 7 the included angle of each of which is twenty degrees, it is of a given width and a given thickness, and has at least two openings therein, all according to the usual custom incident to the production of safety-razor blades in general.

Each jaw 1 has a pair of lugs 8 on the inside, and these lugs are perforated laterally to receive the rod 3. Preferably the lugs 8 are struck or punched out of the jaws 1, as shown.

The spring 4 is V-shaped, and the rod 3 extends through the inner, approximately semi-circular part of said spring, while the outer ends of said spring bear against the 5 inner faces of the jaws 1 at their rear ends. The spring 4, after leaving the rod 3, curves outwardly in opposite directions to engage the rear-end portions of the jaws 1. Thus it is seen that the spring 4 frictionally 10 engages the rod 1 and so holds said rod against endwise movement in the lugs 8, while at the same time pressing outwardly or apart the rear ends of the jaws 1 and so forcing the front ends of said jaws toward each other. 15 The portions of the inner faces of the jaws 1 that are in front of the studs 5 are the parts that bear directly on the blade 6, and each of such bearing parts is formed at an angle of approximately ten degrees to 20 the exterior angle of the corresponding side of the holder, as will presently be more fully explained.

There is a lateral bend in each jaw 1 a short distance from the back edge of said 25 jaw, which bend forms exteriorly what may be termed a shoulder 9. The angle which a line drawn from the shoulder 9 of either jaw 1 to the exposed cutting edge 7 of the blade 6 in the holder, on the same side of 30 said cutting edge with said shoulder, forms with the gripping part of said jaw, which is in front of the studs 8, is an angle of approximately 10°, and there is a clearance between such line and the adjacent face of the 35 jaw forward of the shoulder—see broken lines in Fig. 2. Thus it is seen that the parallel sides of the blade 6 are gripped between two parallel surfaces of the jaws 1, such surfaces extending from the studs 5 to 40 the front edges of said jaws, and that the holder and blade can be held on a flat surface at an angle to said parallel surfaces and the sides of the blade of ten degrees, bearing only at the under shoulder 9 and the 45 under side of the exposed cutting edge 7. Such being the case, the holder and blade can be moved about on a hone without contact with said hone except by the under shoulder 9 and the under side of the exposed 50 cutting edge 7, and said under side of said cutting edge consequently must be ground or sharpened at the required ten-degree angle. Without the clearance which exists between the hone and the under sides of the 55 holder and blade, the holder would be liable to become unevenly worn and thus fail properly to support the blade while being sharpened, with the result that the required angle of the cutting edge of the blade could not 60 be obtained.

The studs 5 being set in one of the jaws 1, it is necessary to provide in the other jaw openings 10—10 to receive the heads of said lugs when the jaws are closed. Due to the fact that the studs 5 pass through 65 the blade 6 into the openings 10, and that the spring 4 causes the jaw to grip said blade tightly, the latter is held very securely in place during the honing operation.

In practice, the jaws 1 back of the shoulder 9 are gripped and forced toward each other at their rear ends, against the resiliency of the spring 4, thus separating the front ends of said jaws, the blade 6 is inserted between such ends and over the studs 70 5, with the latter in the holes in the blade, and said jaws are released to said spring. The blade 6 is now securely supported and held with a portion of the same projecting 75 beyond the front edges of the jaws, and the holder with the blade is placed on a stone and moved about thereon to whatever extent may be necessary to hone the under side of the exposed cutting edge 7. Then the holder is turned over and the other side 80 of the exposed cutting edge 7 is honed. Next the jaws 1 are again opened, and the blade 6 is removed and replaced in reverse position. And finally the newly exposed cutting edge 7 is honed first on one side and 85 then on the other, as was the first cutting edge, when the blade, now with both cutting edges sharp, and ready for use, is removed from the holder.

More or less change in the shape, size, 90 construction, and arrangement of some or all of the parts of this holder may be made, without departing from the spirit of my invention or exceeding the scope of what is claimed.

What I claim as my invention, and desire to secure by Letters Patent, is—

The combination, in a safety-razor-blade holder, with a sheet-metal jaw having lugs punched out intermediate of the ends of the 100 same, and provided with inserted studs, and a second sheet-metal jaw having lugs punched out intermediate of the ends of the same, and perforated to form openings to receive said studs, both of said jaws having 105 blade-gripping parts, of a rod extending through all of said lugs, and an approximately V-shaped spring, the free terminals of which extend outwardly, mounted with 110 its heel on said rod and with the free end portions only of said terminals engaging the rear terminal portions of said jaws adjacent to the rear edges thereof.

HENRY S. NODDINGS.
